UNITED STATES PATENT OFFICE.

JAMES J. FIFIELD, OF BOSTON, MASSACHUSETTS.

REPEATING-CLOCK.

SPECIFICATION forming part of Letters Patent No. 618,406, dated January 31, 1899.

Application filed January 28, 1898. Serial No. 668,325. (No model.)

To all whom it may concern:

Be it known that I, JAMES J. FIFIELD, a citizen of the United States, residing at Boston, in the county of Suffolk and State of Massachusetts, have invented certain Improvements in Automatic Striking Mechanism for Repeating-Clocks, of which the following is a specification.

The object of my invention is to simplify and improve the construction of that class of clocks which automatically repeat the hour immediately after or before striking the half-hour or any other predetermined divisional part of an hour which the clock may be designed to strike, so that a person hearing the said divisional part of the hour struck may at once know the correct time without seeing the dial.

To this end my invention consists in the combination, with the mechanism which is tripped by the rotation of the arbor, of the minute-hand for striking divisions of an hour, of a count-wheel forming a portion of the striking-train and having its circumference enlarged to contain the required number of notches necessary to produce a repetition of the striking of the hour as often as the half-hour or other divisional striking mechanism is brought into action, the striking-train being correspondingly enlarged and properly timed to produce the desired results.

In the accompanying drawings, Figure 1 is a rear elevation of a clock-movement having my improvements applied thereto. Fig. 2 is an end elevation of the same. Fig. 3 is a view of the count-wheel.

In the drawings, A represents the framework of a clock-movement.

B is the going-train, and C the striking-train, which is provided with a count-wheel D of double the usual circumference and having two adjoining sets of notches for each hour, each two sets for each particular hour being separated from the next two sets by the usual deep notch b, into which the counting-arm c drops in the manner common to all striking-clocks to permit the hooked end of the stop-lever d to catch over a pin on the wheel 12 to arrest the movement of the striking-train after the hammer E has struck the required number of blows on the spiral-wire gong or bell G.

H is a second bell, preferably of a tone different from that of the hour bell or gong G and adapted to be struck by a separate hammer I to sound the half-hours. The tail of this hammer, which is fulcrumed on a stud or pivot e, lies in the path of an adjustable wiper-arm h, secured to the arbor 15 of the minute-hand, by which the hammer is raised and released to give the blow on the bell H.

The minute-hand arbor 15 has secured to it just inside of the framework a disk k, which is provided with the usual pin or projection 20, acting on the lever m to liberate or set in action the striking mechanism on the hour, said disk being also provided with an extra pin n, which is located just opposite to the pin 20, and also in turn acts on the lever m to again set in action the striking-train C to repeat the hour just after the striking of the half-hour on the bell H, thus at once indicating to what hour it belongs and enabling a person to know the time without seeing the dial, which will often be found a great convenience, especially at night. It will be obvious that by properly adjusting the wiper-arm h on the minute-hand arbor the half-hour may be struck just before instead of immediately after the repetition of the striking of the hour.

If the clock is to be constructed to strike quarter-hours, the disk k on the minute-hand arbor would be provided with three extra pins or projections n instead of one, as above described, (four in all,) located at uniform distances from each other, and the notches in the count-wheel would then be arranged for repeating the hour every fifteen minutes immediately after or before the striking of the quarters of the hour on the bell H, and in like manner for every division of an hour which the clock is designed to strike. Bells of different tones are preferably employed to indicate the different divisions of an hour, the wiper-arm of the minute-hand arbor being adjusted to cause the hammer I to be released at the exact moment required, which will be immediately followed or preceded by the setting in action of the hour-striking train by the particular pin of the disk k provided for the purpose.

Instead of employing a second hammer and a second bell for striking the divisions of an

hour it will be obvious that the tail of the hammer E may be arranged to be raised and released by the wiper-arm h, in which case both the hours and the divisions of the same 5 would be struck on the same bell; but I prefer to use a separate hammer and bell for two reasons: First, a different-toned bell can be employed for striking the divisions of an hour, and, second, it enables the divisions of 10 an hour to be struck before repeating the hour, whereby sufficient time is afforded for the hammer to be raised for the blow to be struck for the divisions of an hour without interfering with the repetition of the previous 15 hour.

What I claim as my invention, and desire to secure by Letters Patent, is—

1. An hour-repeating clock comprising a time mechanism, a bell and hammer for striking the divisional parts of an hour, an arm on the minute-hand arbor for operating said bell-hammer, an hour-striking mechanism having a count-wheel notched for hours only and having its notches arranged in successive series of equal number and each equal series separated by a deep notch, to receive the hooked end of the usual counting-arm of the hour-striking mechanism, and a plurality of pins carried by a disk or arm on the minute-hand arbor to respectively trip the counting-arm on the hour and then trip it again to repeat the hour contiguous to the sounding of the divisional parts of the hour, substantially as set forth.
2. An hour-repeating clock comprising a time mechanism, a bell and hammer for striking the divisional parts of an hour, a wiper or tappet arm on the minute-hand arbor to

directly engage the tail of the bell-hammer and cause it to strike divisional parts of an hour, an hour-striking mechanism having a count-wheel provided with hour-notches only and having said notches arranged in successive series of equal number and each equal series separated by a deep notch to receive 45 the hooked end of the usual counting-arm of the hour-striking mechanism, a disk secured on the minute-hand arbor and provided with the usual pin for releasing the counting-arm on the hour and also having an auxiliary pin 50 to again release the counting-arm to cause the repeating of that hour contiguous to the striking of the divisional part or parts of an hour, substantially as described.

3. The combination with a time mechanism 55 and a striking mechanism for the divisional parts of the hour actuated from the minute-hand arbor, of an hour-striking mechanism provided with a count-wheel having hour-notches only, said notches for every hour being repeated in equal number and separated by a deep notch, a counting-arm forming part of the hour-striking mechanism and having its hooked end engaging the count-wheel, and a disk on the minute-hand arbor provided 60 with a pin to release the counting-arm on the hour and with an auxiliary pin to again release it to repeat the hour contiguous to the striking of the divisional parts of the same hour, substantially as described.

Witness my hand this 26th day of January, 70
A. D. 1898.

JAMES J. FIFIELD.
